POUNDING TOY

Bill Markham, Los Angeles, Calif., assignor to Lakeside
Industries, Inc., Minneapolis, Minn., a corporation of
Delaware

Filed Nov. 8, 1962, Ser. No. 72,438

Term of patent 14 years

(Cl. D34—15)

FIG. 1

FIG. 2

FIG. 3

FIG. 4

FIG. 1 is a perspective view of my pounding toy embodying my new design with pounding pegs omitted for convenience of illustration;

FIG. 2 is a perspective view thereof with pounding pieces in place;

FIG. 3 is a fragmentary sectional view thereof taken as on line 3—3 of FIG. 2; and

FIG. 4 is a sectional view thereof taken as on line 4—4 in FIG. 2, the bottom being substantially the same in appearance as the top.

I claim:

The ornamental design for a pounding toy, as shown and described.
